UNITED STATES PATENT OFFICE

JOSEPH SHADLOWSKY, OF PASSAIC PARK, NEW JERSEY

DESIGN FOR A GARMENT BUTTON

Application filed December 29, 1931. Serial No. 42,279. Term of patent 3½ years.

To all whom it may concern:

Be it known that I, JOSEPH SHADLOWSKY, a citizen of Russia, residing at Passaic Park, in the county of Passaic and State of New Jersey, have invented a new, original, and ornamental Design for Garment Button, of which the following is a specification, reference being had to the accompanying drawings, forming part thereof.

Fig. 1 is a plan view of a garment button showing my new design.

Fig. 2 is a cross section thereof taken on line 2—2 of Fig. 1.

I claim:

The ornamental design for a garment button as shown.

JOSEPH SHADLOWSKY.
